UNITED STATES PATENT OFFICE.

JAMES J. B. McELRATH, OF CENTRE, ALABAMA.

DESIGN FOR A MATCH-BOX.

SPECIFICATION forming part of Design No. 29,435, dated October 4, 1898.

Application filed August 26, 1898. Serial No. 639,615. Term of patent 7 years.

To all whom it may concern:

Be it known that I, JAMES J. B. McELRATH, a citizen of the United States, residing at Centre, in the county of Cherokee and State of Alabama, have invented and produced a new and original Design for a Match-Box, of which the following is a specification, reference being had to the accompanying drawings, forming a part thereof.

10 Figure 1 is a plan view of a match-box embodying the features of my design, and Fig. 2 is a transverse section through the body portion of the match-box and its pockets.

15 The design consists in a body having a con-

per portion of the shield apparently receiving the lower ends of the limbs of a compass. A square crosses the compass and apparently connects with the central upper portion of the shield, and in the space between the square and the limbs of the compass the letter "G" appears, while upon the shield-like body pockets are apparently formed.

I claim—

20 The design for the match-box herein shown and described.

JAMES J. B. McELRATH.
